A. LEVINE

GOLF BAG AND BASE THEREFOR

Filed Feb. 15, 1923

FIG. 2.

FIG. 1.

Inventor
By *Abraham Levine*
Attorney *William S. Gluck*

UNITED STATES PATENT OFFICE.

ABRAHAM LEVINE, OF ELIZABETH, NEW JERSEY, ASSIGNOR TO PRESTO METAL STAMPING CORPORATION, OF NEW YORK, N. Y., A CORPORATION OF NEW YORK.

GOLF BAG AND BASE THEREFOR.

Application filed February 15, 1923. Serial No. 619,800.

To all whom it may concern:

Be it known that I, ABRAHAM LEVINE, a citizen of Russia, and having a residence at 457 Walnut Street, in the city of Elizabeth, State of New Jersey, have invented certain new and useful Improvements in Golf Bags and Bases Therefor, of which the following is a specification.

My invention relates generally to bags or receptacles employed for containing and conveniently carrying golf clubs and commonly called "caddy-bags." Such bags are usually made cylindrical in form, one end being open to permit of the insertion of the golf-clubs, the peripheral portion being of some heavy textile material and a strap and handle may be applied thereto to allow of conveniently carrying the bag over the shoulder.

I find that it is desirable to employ for the body of such golf or caddy bags a material which possesses certain characteristics, among which are durability, lightness and flexibility and I find these characteristics in materials such as canvas and cloth.

As will be understood by those conversant either with the manufacture, sale or use of golf bags, these bags should retain their shape in all directions against collapse or undue distortion as otherwise the full function of such container will not be attained.

As is obvious, the bag bottom is that part which is subject not only to the greatest strain and wear and tear because of the fact that it supports the golf clubs which are frequently dropped into the bag and strike it forcibly, but also because of the fact that this bottom is additionally subjected to the wearing action arising when the bag is rested on its bottom or is dragged along with the bottom in contact with the ground. The use of a material such as leather which obviously must be of a heavy grade is not desirable, as such material is not only expensive but cannot be worked and shaped readily and economically as required, as will appear hereinafter.

Ordinarily, golf bags are handled by caddies. Frequently, however, players dispense with caddies and carry the bag themselves. In such an event it is highly desirable that these bags be of a character as to remain upright when so positioned, so that on the one hand the several clubs may be available for ready selection for the different strokes,

and on the other hand, the necessity for stooping for the bag at the stroke end is avoided.

Attempts hitherto made to give golf bags the above mentioned characteristics by the employment of a flanged metallic member which forms the bottom and lower part of the side or peripheral wall of the bag and to which the body of the bag is secured have been attended by the necessary objection arising from the dimensional characteristic of the bottom employed, namely, that parts of the bag must be secured together and more particularly the bottom to the side wall, either from the outside or through the open top end of the bag because the lower end of the bag is necessarily closed while such bottom is being attached. This method of procedure is both inconvenient and expensive. A closed bottom of this character is open to the further objection incident to the employment of a metallic bottom, against which the golf clubs are brought forcibly, to the detriment of both, and with the accompaniment of objectionable clatter. Attempts to avoid this by having this bottom lined with another material are necessarily expensive and add to the weight of the bag.

These objections and conditions I overcome to a great extent by the employment of such a structure as permits a procedure whereby the bag parts are united to form the bag structure generally, except for the complete closing of the bottom end while the bag is open at both ends, and then the bottom end is closed to form the desired bottom closure of the bag, such closure member having those characteristics which are desired because of their forming an unobjectionable bottom rest and support for the clubs.

Among the more important objects of my invention therefore are: a procedure for the manufacture of caddy bags whereby the bottom end of the bag is closed after the caddy bag frame structure is fully completed; a procedure for the manufacture of caddy bags whereby the bottom end of the bag is first partly closed to substantially complete the bag frame and is then fully closed; the provision of a bag bottom, adjacent portions of which are made of different materials; the provision of a bag bottom adjacent portions of which are made of ma-

aterials having different predetermined characteristics; the provision of a metal annulus adapted to form the outer part of the bag bottom; the provision of a flanged metal annulus adapted to form means for supporting the bag at a spaced distance above the ground; the provision of a flanged annulus adapted to form the lower part of the periphery of the bag; the provision of a metal annulus which is adapted to simultaneously serve to secure the peripheral and bottom walls in relatively fixed position and to space the bag bottom from the ground; and the provision generally of a new and improved golf bag and base member therefore and of a new procedure for the manufacture of such bags.

For the attainment of these objects and such other objects as may appear or be pointed out in the appended specification, I have illustrated one embodiment of my invention in the accompanying drawings wherein—

Figure 1 is a front elevational view of my improved bag; and

Figure 2 is a cross sectional view.

Upon viewing Figure 1 of the drawings it will be observed that a caddy bag of the type illustrated comprises generally the body portion 10 which is in the form of a cylindrical peripheral wall and is generally of a light, flexible, and durable material such as canvas and the opening at the end which is to form the top may have the reinforcement as shown at 11, which may be of any preferred or desired material such as leather. Such bags are generally closed at the other end to form the closed bottom upon which the golf clubs rest, and such closed bottom is generally desirably so constructed as to form a reinforcement for the bag at that point, or is associated with a construction which acts as such reinforcement. The peripheral canvas wall 10 of such bags are frequently if not generally reinforced between such ends, as by longitudinally arranged stay rods. A bag incorporating these features has been illustrated in the drawings but it will be understood that the use in a bag of one or more of these features is an essential part of my invention only in so far it is so set forth in the appended claims and that my invention is not drawn necessarily even to a complete golf bag. As a matter of fact, as will be observed, one of the main features of my invention resides in an element or part thereof.

As has already been stated the use either of leather or of metal, as hitherto suggested, is unsatisfactory for reasons that will be understood and appreciated as I set forth my novel construction.

The element 15 is an annulus formed preferably of sheet metal by a stamping operation and turned so as to have the doubled

up depending flange 16, the walls 17 and 18 of which form between them the channel 19. As will be observed upon viewing the drawings, the wall 18 extends a substantial distance above the top of the annulus 15 and wall 17 for reasons that will be pointed out shortly.

The channel 19 is of sufficient width to receive within it, the lower end of the canvas body 10 and also the annular sleeve 20 made preferably of a rather heavy weight leather for reasons that will be obvious. For securing these members together in relatively fixed position, I preferably provide the wall 18 of the annulus 15 adjacent its upper end with the openings 21, in which are received rivets 22 which also pass through the canvas 10 and the leather sleeve 20.

To maintain the bag against vertical collapse, I have illustrated the canvas body 10 as reinforced longitudinally by stays 23 secured in pockets 24, formed on the outside surface of the canvas 10. These stays 23 are preferably secured at their upper ends to the reinforce 11 and canvas 10 at the top in any desired manner as by rivets, and at their lower ends these stays are also secured in position by the same rivets 22 which maintain the canvas body 10, leather sleeve 20 and metal annulus 15 as a unit.

The number of these openings 21 that are used, may be as desired, although I find it desirable to employ either three or four depending upon the size of the bag. As is obvious, the number of rivets 22 that are employed as well as the number of stays 23 will correspond in number exactly with the number of holes 21 that are employed. The distance between two predetermined adjacent openings 21 is preferably made greater than between any two others so as to allow sufficient room for the pocket 25 in which golf balls are carried.

By the use of the flanged annulus of the character illustrated in the drawings and thus far described, I attain a number of advantages and functions of which I will now point out the most important one. In assembling the bag bottom, that is in joining the parts 10, 15, 20 and 23, these parts can be appropriately positioned and the rivets driven therethrough without being compelled to work wholly from the outside or from the removed upper end of the bag. It will thus be understood that as a result of the employment of the annulus 15, I am enabled to employ a procedure in golf bag construction, whereby the bag frame is completed in all respects while both ends are open.

The opening in the annulus 15 is closed in accordance with my invention with a material such as leather of a very heavy grade, which as will be observed takes the form of a leather disc 30, secured in position pref-

erably by rivets 31, secured in openings 32 formed in the annulus 15. In this manner I am enabled to provide the golf bag with a single bottom closure of different materials, the peripheral metal part 15, serve particularly to strengthen and unite the parts, being characterized by rigidity, strength, and durability, while the leather center disc 30 serve particularly well as the bag bottom, because of its flexibility, relative softness and sound deadening capacity. Furthermore the depending flange 16 serves to space the bag bottom above the ground for a sufficient distance so as to permit of the inevitable downward bulge of the center of the bottom. This flange serves further as an annular base of a character which will maintain the bag upright when desired.

It will be understood further, that either part of the bag bottom can be readily replaced. For instance should the leather disc 30 require replacement, all that is necessary is that the rivets 31 be knocked off, and a new leather disc secured in position. If the annulus 15 requires replacement, the rivets 22 and 31 are knocked off, and the parts replaced with a new annulus as described above.

It will be observed that one of the essential features of my invention consists in having a bottom section made up of trans-

versely juxtaposed parts of dissimilar materials as described. It will be of course understood that additional layers of any desired materials may be superposed thereon. Where therefore I employ the word "Single" as applied to the bottom, I merely intend to convey the idea that reference is had to a single layer regardless of whether this layer serves as the complete bottom, or merely as one layer or section of a bottom made of superposed layers or sections.

Having thus described my invention and illustrated its use, what I claim as new and desire to secure by Letters Patent is the following:

As an improved article of manufacture, a metal annulus adapted to form part of the golf bag bottom, said annulus being provided with a doubled-up depending flange providing spaced walls arranged to receive the lower end of the bag body therebetween with the outer wall extending above the inner wall, the inner wall being provided with a horizontal ring to which a bottom may be secured, clamping means for the bag body engaging the upwardly extended portion of the outer wall above the plane of the horizontal ring.

In witness whereof, I have hereunder signed my name this 13 day of February, 1923.

ABRAHAM LEVINE.
